(57) **CLAIM**

The ornamental design for a computer display screen or portion thereof with animated graphical user interface, as shown and described.

DESCRIPTION

FIG. 1 is a front view of a computer display screen or portion thereof with animated graphical user interface showing the first image in a first embodiment of the claimed design; FIG. 2 is the second mage thereof; FIG. 3 is the third image thereof;

FIG. 4 is a front view of a computer display screen or portion thereof with animated graphical user interface showing the first image in a second embodiment of the claimed design; FIG. 5 is the second image thereof; FIG. 6 is the third image thereof; and, FIG. 7 is the fourth image thereof.

The appearance of the transitional image sequentially transitions between the images shown in FIGS. 1-3 and 4-7. The process or period in which one image transitions to another image forms no part of the claimed design.

The longer-incremented broken-line showing of a portion of a computer and the shorter-incremented broken line showing of a display screen of the computer, as well as the features within the interface, are included for the purpose of illustrating environmental structure and form no part of the claimed design.
